UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

DEVICE FOR GUIDING, CLEARING, AND TENSIONING YARN.

1,392,515.

Specification of Letters Patent.

Patented Oct. 4, 1921.

Application filed April 12, 1921. Serial No. 480,636.

To all whom it may concern:

Be it known that I, JOHN O. McKEAN, a citizen of the United States, and resident of Westfield, in the county of Hampden and State of Massachusetts, have invented a new and useful Improvement in Devices for Guiding, Clearing and Tensioning Yarn, of which the following is a specification.

The object of my invention is to provide certain improvements in the construction, form and arrangement of the several parts of a device for guiding, clearing and tensioning yarn, whereby the life of the device is materially lengthened; in which the parts which are subject to wear may be readily replaced; in which the rotation of the gravity operated disk by the yarn is assured; in which the depending split pin on which the disk is loosely mounted may be readily inserted and removed; and in which all liability of the catching of the yarn on the device when threading the same is eliminated.

This invention relates more particularly to improvements in the device covered by my application, filed March 11, 1921, Serial No. 451485.

A practical embodiment of my invention is represented in the accompanying drawings, in which,

Fig. 1 represents the device in top plan.

Fig. 2 represents the same in side elevation.

Fig. 3 represents the device in bottom plan.

Fig. 4 represents the same in front elevation.

Fig. 5 represents the device in rear elevation.

Fig. 6 represents a section taken in the plane of the line VI—VI of Fig. 1.

Fig. 7 represents the gravity operated disk in side elevation.

Fig. 8 represents the same in bottom plan.

Fig. 9 represents the removable and reversible yarn support grid in perspective.

Fig. 10 represents the split pin on which the gravity operated disk is mounted, in perspective.

The bracket is preferably a casting and it comprises a resilient yoke, the lower member of which is denoted by 1 and the upper member by 2. These two members are provided with lateral extensions 3 and 4 respectively, forming between them a slit 5

for the passage of the yarn. The lateral extension 3 may be provided with a downwardly extended ear 6, and the lateral extension 4 may be provided with a lug 8 from which a pin 9 projects downwardly across the slit 5 to serve as a guide for the yarn as it passes from the slit.

The upper member 2 is sprung out of its normal position to vary the width of the slit 5 without changing the parallelism of its walls, by means of an adjusting screw, the shank 10 of which passes through the upper member 2 across the yoke and into screw-threaded engagement with the lower member 1, the head 11 of which screw is preferably countersunk in a recess 12 in the upper member 2. As the device is shown the screw is arranged to spring the upper member 2 toward the lower member 1 of the yoke to narrow the yarn slit 5, the resiliency of the yoke serving to spring the members apart to widen the slit as the screw is turned back.

The parts hereinabove described serve to act as a very effective and simple yarn clearer or slub catcher which may be readily adjusted to the minutest degree, for different sizes of yarn and then will engage bunches, slubs, knots or other enlarged portions of the yarn for clearing the same.

The bracket may be supported in any suitable manner on the bar 13 of the machine, as for instance by providing the lower member of the yoke with a hollow lug 14 through which the bar 13 extends; a set screw 15 being provided for securing the bracket on the bar.

An arm 16 extends laterally from the lower member 1 of the yoke, from which arm project forwardly and rearwardly respectively, fingers 17 and 18, the rearwardly extended finger 18 having a hooked-end 19 which serves as a guide and keeper for the yarn as it enters the device. The arm 16 is provided with a depressed portion 20 adjacent the lower member 1 of the yoke over which the yarn leads to the tension device to be immediately described.

A gravity tension device for the yarn is constructed and arranged as follows:—

A guard portion 21 extends rearwardly from the lateral extension 4 of the upper member 2 of the bracket and overlaps on the inside of the forwardly extended finger 17, leaving a space 22 for the introduction

of the yarn when threading the same. The upper member is also provided with an overhanging portion 23 forming a bridge leading from the rear end of the guard 21 to the 5 front end of the said upper member.

A split pin extends through the overhanging portion 23 and projects downwardly therefrom to a point below the yarn support to be hereinafter described, which pin 10 is frictionally held in its position so that it may be removed from the overhanging portion when so desired. In the present instance I have shown this pin as a cotter pin, the branches of which are denoted by 24, 25 15 and the laterally turned head of which is denoted by 26. This laterally turned head end of the pin serves as a convenient handle for manipulating the pin. The bending of the head end of the pin also insures the 20 keeping of the branches 24, 25 of the pin together when the pin is inserted into its operative position, and does not permit the spreading of the branches as is the tendency where the head end of the pin is not turned 25 laterally.

The overhanging portion 23 is provided with an uprising guard 27 for preventing the yarn from being caught on the head 26 of the split pin, it being understood that the 30 head of the split pin may be swung laterally into a position in front of the guard for more completely protecting the head of the pin from engagement by the yarn.

The removable and reversible yarn support which forms a part of the tensioning device for the yarn comprises a U-shaped grid 28 provided with branches 29, 30, which span the space between the lower member 40 of the yoke and the forwardly projecting finger 17 of the lateral arm 16. In the present instance one branch of this skeleton support or grid is inserted through a hole in the finger 17 and both branches are inserted into holes in the lower member of the 45 yoke. This U-shaped grid is removable and reversible so that when the top of the grid becomes worn by the yarn, the grid may be removed and replaced to present new surfaces, and when these new surfaces become 50 worn, the grid may be replaced by a new grid.

A set screw 31, carried by the lower member of the yoke is arranged in position to be 55 turned into clamping engagement with one of the branches of the grid for holding the same against unintentional removal.

The weighted disk 32 which forms a part of the tensioning device is loosely mounted 60 on the depending split pin and normally rests upon the removable and reversible grid. This weighted disk is provided with an axially arranged depending hollow lug 33, which projects below the top of the yarn support, in the present instance between the 65

branches of the grid, in position to be frictionally engaged by the yarn, whereby the disk is rotated as the yarn passes between it and the support, thus providing an even wear on the bottom of the said disk.

70

It will be seen that by the provision of a skeleton support for the yarn as it passes under the weighted disk, I am enabled to produce a device in which all tendency of the filling up of the device with lint, seed or other foreign matter under the weight, which would tend to render the weight ineffective, is eliminated.

75

It will also be seen that by the provision of a removable and reversible skeleton support for the yarn I am enabled to materially increase the life of the device as a whole.

80

Another valuable feature is the provision of the depending axially arranged lug for 85 the weighted disk, together with means for guiding the yarn into frictional engagement with said lug so that the wear may be equalized on the bottom of the disk.

85

The parts shown and described, but not 90 claimed herein, which relate more particularly to the construction of the yarn clearer or slub catcher form the subject matter of a co-pending application filed by me on September 16, 1920, Serial No. 410637.

95

It is evident that various changes may be resorted to in the construction, form and arrangement of the several parts without departing from the spirit and scope of my invention; hence I do not wish to limit myself 100 to the particular embodiment herein shown and described, but

What I claim is:—

1. In a tension device a removable fixed grid forming, a skeleton yarn support, a gravity operated disk normally resting on said support and having an axially arranged depending lug projecting below the top of the yarn support, and guiding means for causing the yarn to contact with the said lug. 105

2. In a tension device, a removable and reversible grid forming a skeleton yarn support, a gravity operated disk normally resting on said support and having an axially arranged depending lug projecting between the branches of the grid, and guiding means for causing the yarn to contact with the said lug. 115

3. In a tension device, a bracket, a fixed yarn support carried thereby, a vertically disposed pin depending from the bracket, a gravity operated disk loosely mounted on said pin and normally resting on said fixed yarn support, said disk having an axially arranged hollow depending lug projecting below the top of the yarn support, and guiding means for causing the yarn to contact with the said lug. 120

4. In a tension device, a bracket, a yarn

125

- support carried thereby, a depending split pin frictionally held in the bracket, the head end of the split pin being laterally bent, forming a handle, and a gravity operated disk loosely mounted on said pin and normally resting on said support.
5. In a tension device, a bracket, a yarn support carried thereby, a depending split pin frictionally held in the bracket, the head 10 end of the split pin being laterally bent, forming a handle, a gravity operated disk loosely mounted on said pin and normally resting on said support, said disk having an axially arranged hollow depending lug projecting below the top of the yarn support, and guiding means for causing the yarn to contact with the said lug.
6. In a tension device, a bracket, a yarn support carried thereby, said bracket having 20 a portion overhanging the yarn support, a pin depending from said overhanging portion, a gravity operated disk loosely mounted on said pin and normally resting on said support, said disk having an axially arranged hollow depending lug projecting below the top of the yarn support, and guiding means for causing the yarn to contact with the said lug.
7. In a tension device, a bracket, a yarn support carried thereby, said bracket having 30 a portion overhanging the yarn support and provided with an uprising guard, a depending split pin frictionally held in said overhanging portion, said pin having a laterally bent head end forming a handle arranged to be turned into a position back of said guard, and a gravity operated disk loosely mounted on said pin and normally resting on said support.
- 40 8. In a tension device, a bracket, a yarn support carried thereby, said bracket having a portion overhanging the yarn support and provided with an uprising guard, a depending split pin frictionally held in said overhanging portion, said pin having a laterally bent head end forming a handle arranged to be turned into a position back of said guard, a gravity operated disk loosely mounted on said pin and normally resting on said support, said disk having an axially arranged hollow depending lug projecting below the top of the yarn support, and guiding means for causing the yarn to contact with the said lug.
- 45 9. A tension device comprising an integral resilient yoke, the upper and lower members of which have lateral extensions forming between them a slit for the passage of the yarn, means for springing one of the members toward the other member to narrow the slit, a yarn support carried by the lower member, a depending pin carried by the upper member, and a gravity operated disk loosely mounted on said pin and normally resting on said support.
- 55 10. A tension device comprising an integral resilient yoke, the upper and lower members of which have lateral extensions forming between them a slit for the passage of the yarn, means for springing one of the members toward the other member to narrow the slit, a skeleton yarn support carried by the lower member, a depending pin carried by the upper member, and a gravity operated disk loosely mounted on said pin and normally resting on said support.
11. A tension device comprising an integral resilient yoke, the upper and lower members of which have lateral extensions forming between them a slit for the passage 80 of the yarn, means for springing one of the members toward the other member to narrow the slit, a yarn support carried by the lower member, a depending pin carried by the upper member, a gravity operated disk 85 loosely mounted on said pin and normally resting on said support, said disk having an axially arranged hollow depending lug projecting below the top of the yarn support, and guiding means for causing the 90 yarn to contact with the said lug.
12. A tension device comprising an integral resilient yoke, the upper and lower members of which have lateral extensions forming between them a slit for the passage 95 of the yarn, means for springing one of the members toward the other member to narrow the slit, a skeleton yarn support carried by the lower member, a depending pin carried by the upper member, a gravity operated disk loosely mounted on said pin and normally resting on said support, said disk having an axially arranged hollow depending lug projecting below the top of the yarn support, and guiding means for causing the 100 yarn to contact with the said lug.
13. A tension device comprising an integral resilient yoke, the upper and lower members of which have lateral extensions forming between them a slit for the passage 110 of the yarn, means for springing one of the members toward the other member to narrow the slit, said lower member having a laterally extended arm provided with a forwardly extended finger, a U-shaped yarn support grid having one of its branches passed through the forwardly extended finger and both of its branches inserted into said lower member, a depending pin carried by the upper member, and a gravity operated disk loosely mounted on said pin and normally resting on said grid.
14. A tension device comprising an integral resilient yoke, the upper and lower members of which have lateral extensions 115 forming between them a slit for the passage of the yarn, means for springing one of the members toward the other member to narrow the slit, said lower member having a laterally extended arm provided with a 120
15. A tension device comprising an integral resilient yoke, the upper and lower members of which have lateral extensions 125 forming between them a slit for the passage of the yarn, means for springing one of the members toward the other member to narrow the slit, said lower member having a laterally extended arm provided with a 130

forwardly extended finger, a U-shaped yarn support grid having one of its branches passed through the forwardly extended finger and both of its branches inserted into 5 said lower member, a depending pin carried by the upper member, a gravity operated disk loosely mounted on said pin and normally resting on said grid, said disk having

an axially arranged hollow depending lug projecting between the branches of the grid, 10 and guiding means for causing the yarn to contact with the said lug.

In testimony, that I claim the foregoing as my invention, I have signed my name this 9th day of April, 1921.

JOHN O. McKEAN.
